UNITED STATES PATENT OFFICE.

HERMAN J. HEIDGERKEN, OF PHILIPSBURG, MONTANA.

WATER-HEATER.

1,212,636.

Specification of Letters Patent. Patented Jan. 16, 1917.

Application filed January 26, 1914. Serial No. 814,510.

To all whom it may concern:

Be it known that I, HERMAN J. HEIDGERKEN, a citizen of the United States, residing at Philipsburg, in the county of Granite, State of Montana, have invented certain new and useful Improvements in Water-Heaters; and I do hereby declare the following to be a full, clear, and exact description of the invention, such as will enable others skilled in the art to which it appertains to make and use the same.

This invention relates to improvements in water heaters, and particularly to devices of this character in which a complete circulation of water is produced.

The principal object of the invention is to provide a simple device of this character by means of which water can be quickly and easily heated, the device being adapted for use in connection with brooders and incubators, or may be used for heating a room.

Other objects and advantages will be apparent from the following description, when taken in connection with the accompanying drawings.

In the drawings: Figure 1 is an elevation of my water heater. Fig. 2 is a vertical longitudinal sectional view therethrough. Fig. 3 is a horizontal sectional view on the line 3—3 of Fig. 2. Fig. 4 is a horizontal sectional view on the irregular line 4—4 of Fig. 2 looking upwardly.

Referring particularly to the accompanying drawings, 10 represents the burner of a lamp which has the tubular wick 11. Carried by the outer sleeve of the burner is a horizontal circular disk 12 provided with a plurality of draft openings 13 and a vertical peripheral flange 14. Disposed above the burner is a vertical cylinder 15, this cylinder having formed thereon a surrounding water jacket 16. Disposed concentrically around the water jacket 16 and separated from this jacket by the hot air space 17 is a second water jacket 18. The lower end of this outer water jacket is provided with a depending flange 19 which rests on the disk 12 inwardly of the flange 14. In one side of this depending flange is a door 20 carrying a suitable pane of mica, glass or the like. This door makes it possible to view the burner and easily light the lamp. Extending across the hot air space 17 and establishing communication between the lower ends of the water jackets 16 and 18 is a pipe 21. Disposed above the water jackets

is a suitable water tank 22, and connecting the lower end of this tank with the lower end of the outer water jacket 18 is a cold water conveying pipe 23, while connecting the upper portion of the tank at the opposite side thereof, and near the upper end, with the upper end of the inner water jacket 16 is a hot water conveying pipe 24, this pipe carrying the water as it is heated, into the tank. A short pipe 25 establishes communication between the upper end of the outer water jacket 18 and the pipe 24, so that the water in the said outer water jacket will flow upwardly through the pipe 24 into the tank 22, as it becomes heated.

It will be noted that the lower end of the water jacket 16 terminates at a point above the lower end of the jacket 18. This provides a space for the circular flame from the wick and permits the flame to spread and pass up the space 17. The lower end of the dead air chamber 15 extends below the lower end of the jacket 16, and terminates at a point over the center of the burner.

It will thus be seen that when the tank 22 and the water jackets 16 and 18 are filled with water, and the wick ignited, that heat will flow between the inner and outer water jackets, and thoroughly heat the water in the jackets. As the water heats, it will rise to the upper ends of the jackets and flow through the pipes 24 and 25 into the tank 22, the cooler water in the lower part of the tank going down the pipe 23 and entering the jacket 18 near the lower end. After the wick has been burning for a period of time, the water in the tank 22 will all become properly heated.

While I have shown the heater used in connection with an oil lamp, it will of course be understood that a gas burner can be used as well. Also, instead of the tank 22, the pipes 23 and 24 can be connected together and extended through a brooder or incubator so as to provide a hot water heating system therefor.

The device illustrated in the drawing is especially valuable and applicable to doctors' and dentists' offices and barber shops, as well as for emergency use in bath rooms.

What is claimed is:

In a water heater, a flue, a source of heat within the lower end of the flue, a water chamber formed on and surrounding the flue, a dead air chamber disposed centrally

within the flue and spaced therefrom, a water chamber formed on and surrounding the dead air chamber and spaced from the wall of the flue, a conduit connecting the 5 water chambers, a reservoir, connections between the bottom of the first water chamber and the reservoir, connections between the top of the second water chamber and the reservoir and connections between the first-

named water chamber and the last-named 1. connections to the reservoir.

In testimony whereof, I affix my signature, in the presence of two witnesses.

HERMAN J. HEIDGERKEN.
